Primary Examiner — Freda S Nunn(74) *Attorney, Agent, or Firm* — PatentBest; Andrew
McAleavey(57) **CLAIM**

The ornamental design for a stylus stand and charging station, as shown and described.

DESCRIPTION

This application is related to a U.S. design patent application Ser. No. 29/547,285 entitled "Stylus Stand". That application is incorporated by reference in its entirety.

FIG. 1 is a perspective view of a stylus stand and charging station embodying my new design;

FIG. 2 is a top plan view of the stylus stand and charging station of FIG. 1;

FIG. 3 is a bottom plan view of the stylus stand and charging station of FIG. 1;

FIG. 4 is a side elevational view of one side of the stylus stand and charging station of FIG. 1;

FIG. 5 is a side elevational view of the other side of the stylus stand and charging station of FIG. 1, the stylus stand being radially symmetric about its center such that the sides are mirror images of one another; and,

FIG. 6 is a perspective view of the stylus stand and charging station of FIG. 1 in use.

The broken lines immediately adjacent the shaded areas represent the bounds of the claimed design, while all other broken lines are directed to environment and are for illustrative purposes only; the broken lines form no part of the claimed design.
